UNITED STATES PATENT OFFICE.

EDWARD J. MUNDALE, OF FROST, MINNESOTA.

EXCAVATING-MACHINE.

No. 923,290.

Specification of Letters Patent.

Patented June 1, 1909.

Application filed June 29, 1908. Serial No. 440,778.

To all whom it may concern:

Be it known that I, EDWARD J. MUNDALE, a citizen of the United States, residing at Frost, in the county of Faribault and State of Minnesota, have invented certain new and useful Improvements in Excavating - Machines; and I do hereby declare the following to be a full, clear, and exact description of the invention, such as will enable others skilled in the art to which it appertains to make and use the same.

My invention has for its object to provide an improved excavating machine especially adapted for use in digging trenches or ditches in which to lay drain pipes, sewer pipes, water pipes and the like; and to this end it consists of the novel devices and combinations of devices hereinafter described and defined in the claims.

In the accompanying drawings which illustrate the invention, like characters indicate like parts throughout the several views.

Referring to the drawings, Figure 1 is a plan view of the improved excavating machine. Fig. 2 is a side elevation of the machine. Fig. 3 is a vertical section taken on the line $x^3 x^3$ of Fig. 2, some parts being broken away. Fig. 4 is a detail in side elevation, showing on an enlarged scale an end less excavating device, some parts being broken away. Fig. 5 is a front elevation of the parts shown in Fig. 4; and Fig. 6 is a horizontal section taken on the line $x^6 x^6$ of Fig. 4.

The framework 1 of the machine is preferably constructed of metal and is supported by the rear traction wheels 2 and front steering wheels 3. The traction wheels 2 are loosely journaled on an axle 4 that is rigidly secured to the frame 1, while the front wheels 3 are journaled on an axle 5 that is intermediately pivoted to a bracket 6 secured to the front portion of the frame 1. A steering device, not shown, but such as customarily used on traction engines, may be employed to control the oscillatory movements of the axle 4 and, hence, to properly steer the machine. Large spur gears 7 are secured to the hubs of the traction wheels 2, and these mesh with pinions 8 secured on the ends of a transverse counter-shaft 9 mounted in suitable bearings on the intermediate portion of the frame 1 and provided with a large ratchet wheel 10. The ratchet wheel 10 is adapted to be operated upon by a driving pawl 11 carried by the upper end of a lever

12, intermediately pivoted to one side of the frame 1 and connected, by a rod 13, to a short crank 14 which, in turn, is carried by a transverse counter-shaft 15 mounted in suitable bearings on the frame 1. This countershaft 15 carries a pulley 16 and a bevel gear 17.

Mounted on the intermediate portion of the frame 1 is an explosive engine, indicated as an entirety by the numeral 18, and of the parts of which it is only necessary for the purposes of this case to particularly note the crank shaft 19 thereof, which at one end carries a pulley 20 and at its other end is preferably provided with a fly wheel 21. A belt 22, shown only by dotted lines in Fig. 2, runs over the alined pulleys 20 and 16 to impart motion from the engine crank shaft to the transverse counter-shaft 15.

The excavating device comprises a vertically adjustable supplemental frame, upper and lower wheels or sprockets, and a scoop or bucket-equipped endless link chain arranged to run over said wheels or sprockets. The said supplemental frame is preferably made up of vertically elongated laterally spaced metal plates 23, transverse tie bars 24 and vertically extended angle guides or tracks 25, which parts are rigidly connected together and are mounted to move vertically as an entirety. This supplemental frame is guided for vertical movements, preferably by grooved anti-friction wheels 26 that engage vertically extended guide bars 27 secured to the outer sides of the frame plates 23. These guide wheels 26 are mounted on the inwardly projecting arms of bearing brackets 28 rigidly secured to the sides of the frame 1, as best shown in Figs. 1 and 3. One of the bars 27 is provided with rack teeth 29 with which engage a pinion 30 carried by the rear end of a shaft 31 (see Figs. 1 and 3). This shaft 31, at its rear end, is suitably journaled on the right hand bearing bracket 28; and, at its forward end, is journaled in one of the transverse bars of the frame 1, and is provided with a worm gear 32, best shown in Fig. 1. The worm gear 32 (see Fig. 3) is engaged by a worm 33 by the lower end of an upright rod 34 mounted in suitable bearings on the frame 1; and provided, at its upper end, with a hand wheel 35, by means of which the said rod 34 may be rotated in either direction, to thereby, through the connections just described, raise or lower the supplemental excavating frame, at will. It

is, of course, evident that said supplemental frame will be locked in any vertical adjustment by the coöperating worm 33 and worm gear 32.

5 The excavating scoops or buckets 36 are pivotally connected at 36^a, preferably to alternate joints of a pair of laterally spaced parallel link belts 37. These belts 37 run over upper and lower wheels or sprockets 38 that are 10 secured in pairs on counter-shafts 39, journaled in suitable bearings on the side plates 23 of the vertically adjustable supplemental frame. Each scoop or bucket 36 is provided with an intermediately secured inwardly projecting arm 40 that carries an anti-friction wheel 41 at its free end. The wheels 41, throughout the working travel of the scoops 36, run against a guide rail 42 that is rigidly secured to certain of the transverse tie bars 15 24 of the vertically adjustable supplemental frame. This guide rail 42 extends vertically nearly from the top to the bottom of the said supplemental frame and has rearwardly curved upper and lower extremities, and it is 20 25 so disposed in respect to the said link belts 37 and the said wheels 41 that in its action upon the latter it will positively force the scoops into extended or operative positions just before they pass under the lower sprockets 38, and will hold the same in such operative positions until after the said scoops have passed over the upper sprockets.

The transversely opposite links of the two carrier chains 37 are tied together by thin 35 metal plates 43 and 44, the former of which coöperate with the adjacent scoops 36 to hold the excavated dirt, and the latter of which prevent the dirt from falling into the supplemental frame of the excavator.

40 Alternate scoops 36 are preferably formed with serrated or toothed outer edges 45 that project slightly beyond the corresponding edges of the other scoops and serve to loosen the dirt to be taken up by the next following 45 scoop. The plates 43 that tie together transversely opposite links of the belts 37 are provided with inwardly projecting flanges 43^a to which are journaled guide wheels 46 that run on the inner surface of the inwardly projecting flanges of the angle iron rails 25 and thus prevent the scoops 36 from being forced outward beyond their proper line of movement.

When the rollers 41 pass beyond the upper 55 end of the guide rail 42 the scoops are released and permitted to move pivotally backward, as indicated in Figs. 2 and 4. While they are thus turned backward, the scoops are carried against a spring pressed scraper 60 47 which, as shown, is pivoted to brackets 48 secured to the side plates 23 of the vertically movable supplemental frame. A roller 49 is also journaled in the brackets 48. An endless conveying belt 50 runs over the roller 49 65 and over another roller, not shown, which

latter roller will be mounted in suitable supports, preferably at a considerable distance from the rear end of the excavating machine proper.

Motion is transmitted from the counter-shaft 15 above noted to the upper pair of chain wheels or sprockets 38, through the following connections: The bevel gear 17 meshes with a bevel gear 51 on a longitudinally extended counter-shaft 52 mounted in suitable bearings on the frame 1 and provided, at its rear end, with a bevel gear 53. The bevel gear 53 meshes with a bevel gear 54, the hub of which is journaled in a bracket 55 carried by one side of the frame 1. A vertical shaft 56 is passed axially through the gear 54 and is connected thereto by a long key or other suitable connection which will cause said shaft and gear to rotate together but permit the shaft to move vertically in respect thereto. At its upper end, the shaft 56 is journaled in a bearing 57 on the upper end of the vertically movable supplemental frame and is held for vertical movements therewith. A bevel gear 58 on one end of the upper sprocket 39 meshes with a bevel gear 59 on the upper end of the shaft 56.

As is evident, when the engine is running and the driving pawl 11 is in action on the ratchet wheel 10, the machine will be driven 95 slowly forward and the scoop-equipped excavating belts will be kept under constant motion in a direction to cause the scoops to scrape up the dirt and carry the same over onto the discharge belt 50, by which latter the 100 dirt may be carried to a desirable point at the rear of the machine and discharged again back into the ditch. The advance movement of the excavating apparatus may be stopped at any time simply by turning the driving 105 pawl 11 over into an inoperative position.

As is evident, the depth of the ditch that will be dug by the excavator may be varied by vertical adjustment of the supplemental frame and excavating devices carried thereon, and is accomplished by manipulation of the hand wheel 35 and connections already described.

The machine above described may be used for a good many different purposes. It is 115 capable of general use wherever a ditch or trench is to be formed and is especially adapted for use for digging comparatively narrow and deep trenches, such as required for laying drain pipes, water pipes, sewer 120 pipes, gas pipes, etc.

What I claim is:

1. In an excavating machine, the combination with a truck, of an engine carried by the frame of said truck, a connection between 125 the crank shaft of said engine and one of the wheels of said truck, including a pawl and ratchet wheel, and an excavating device carried by said truck and driven from said engine, substantially as described.

2. In an excavating device, the combination with a link belt and guiding and driving wheels therefor, of scoops pivoted to certain of the links of said belt and provided with 50 roller-equipped arms, a guide rail extending along the line of the operative movement of said scoops and coöperating with said roller-equipped arms to hold said scoops projected throughout their operative movement, but 55 permitting the same to turn backward under return movements, and a scraper operative on said scoops while they are turned backward and are making their return movement, substantially as described.
- 10 3. In an excavating machine, the combination with a truck having a main frame and a vertically adjustable supplemental frame, of an endless excavating belt and guiding and driving wheels therefor mounted 60 on said supplemental frame, scoops pivoted to said belt and provided with wheel-equipped arms, a guide rail coöperating with said wheel-equipped arms to hold said scoops projected throughout their operative movements but permitting them to turn 65 backward under return movements, substantially as described.
- 15 4. In an excavating machine, the combination with a truck having a main frame, guide wheels on said main frame, and a vertically adjustable and a vertically extended supplemental frame mounted for coöperation 70 with said guide wheels, of an endless scoop equipped excavating belt and guiding and driving wheels therefor mounted on said supplemental frame, a vertically extended 75 rack secured to said supplemental frame, a shaft mounted on said main frame and provided at one end with a worm gear and at its other end with a spur pinion, the latter 80 meshing with said rack, and an adjustable rod provided with a hand piece and with a worm, the latter meshing with said worm gear, the said connections serving to impart 85 vertical adjustments to said supplemental frame and to lock the same in different vertical positions, substantially as described.
- 20 5. In an excavating device, the combination with a vertically extended frame having endless belt guiding tracks, of a pair of laterally spaced link belts connected together by plates and coöperating guiding and driving wheels mounted on said frame, 90 guide wheels carried by certain of the links of said belts and engaging said guide tracks, scoops pivotally connected to certain of the 95 links of said belts and provided with wheel-equipped arms, and a guide rail coöperating with said wheel-equipped arms to hold said scoops projected throughout their operative movements but permitting them to turn 100 backward under return movements, substantially as described.
- 25 6. In an excavating machine, the combination with a truck having a main frame, 105 guide wheels on said main frame, and a vertically adjustable and a vertically extended supplemental frame mounted for coöperation with said guide wheels, of an endless scoop equipped excavating belt and guiding and driving wheels therefor mounted on said supplemental frame, a vertically extended 110 rack secured to said supplemental frame, a shaft mounted on said main frame and provided at one end with a worm gear and at its other end with a spur pinion, the latter 115 meshing with said rack, and an adjustable rod provided with a hand piece and with a worm, the latter meshing with said worm gear, the said connections serving to impart vertical adjustments to said supplemental frame and to lock the same in different vertical positions, substantially as described.
- 30 7. In testimony whereof I affix my signature in presence of two witnesses.
- 35 8. EDWARD J. MUNDALE.
